PRESSURE WASHER

Joseph Henry Chapman, 109 Pope St.,
Menlo Park, Calif. 94025

Filed Feb. 13, 1969, Ser. No. 15,764

Term of patent 14 years

Int. Cl. D15—06

U.S. Cl. D49—11

Fig. 1

Fig. 2

Fig. 3

FIG. 1 is a perspective view, taken from the front and slightly above and to the left of center, of a pressure washer showing my new design;

FIG. 2 is a side view, taken from the left side, of the pressure washer of FIG. 1;

FIG. 3 is a side view, taken from the right side, of the pressure washer of FIG. 1; and

FIG. 4 is a top view of the pressure washer of FIG. 1, the bottom and rear being conventionally plain.

I claim:

The ornamental design for a pressure washer, substantially as shown and described.
